[57]

ABSTRACT

A toy device wherein a hoop can be rolled and steered along the ground by a cord which is attached to one end of a manually held guide rod. The cord is connected to a coupling ring which is received in one or more transversely extending recesses of the hoop so as to be turnable on but to be held against movement in the circumferential direction of the hoop. By exerting a pull on the cord while the coupling ring travels upwardly and away from the ground, the user can impart to the hoop a driving momentum to thereby accelerate the hoop. The hoop will travel along an arcuate path if the coupling ring is turned to move its point of connection with the cord to the one or the other side of the hoop while the coupling ring is located at the uppermost point of the hoop and if the cord is swung sideways to tilt the hoop.

ROLLING TOY HOOP

BACKGROUND OF THE INVENTION

The present invention relates to toy devices in general, and more particularly to improvements in a hoop which can be rolled along the ground and caused to change the direction of its movement by a combined steering and driving device, preferably a device employing a cord, a string or an analogous elongated flexible member.

It is already known to connect a hoop with a steering and driving device which is fastened to one side of the hoop so that the point of engagement between the steering and driving device and the hoop is more or less fixed and cannot be shifted at will from the one to the other side of the hoop while the latter rolls along the ground. Thus, the upwardly directed pull that can be exerted by the steering and driving device to propel the hoop in a forward direction will be one-sided provided, of course, that the hoop has not been provided with a discrete steering and driving device at each side thereof. Such a hoop cannot be steered and driven along arcuate paths the configuration of which the user of the hoop can control because the position of the point of engagement between the steering and driving device and the hoop cannot be changed during driving at the will of the operator. The manipulation of the hoop is overly complicated if the latter is connected with several steering and driving devices.

SUMMARY OF THE INVENTION

An object of the invention is to provide a novel and improved toy device which includes a hoop and enables the user to control the speed as well as the direction of travel of the hoop by means of a single steering and driving device.

Another object of the invention is to provide a novel and improved coupling between the hoop and the steering and driving means therefor.

A further object of the invention is to provide a versatile toy device of the above outlined character which can be manipulated and enjoyed by children of all ages and both sexes.

An additional object of the invention is to provide a toy device including a hoop which is simple, inexpensive, light-weight and interesting to the user.

The improved toy device comprises a hoop which can roll along the ground, a coupling element which is mounted for turning movement about the hoop, abutment means provided on the hoop to restrict the movement of the coupling element in the circumferential direction of the hoop, and a single combined driving and steering device including a manually operable elongated member one end of which is connected with the coupling element, preferably in such a way that the end of the elongated member can swivel relative to the coupling element but shares all turning movements of the coupling element relative to the hoop.

The coupling element may constitute a ring which is rotatable on a selected portion of the hoop, and the combined steering and driving device may comprise a rigid elongated member which can be held by hand and a flexible elongated member, one end portion of which is connected to the rigid elongated member and the other end portion of which is articulately connected with a single portion of the coupling element.

The rigid elongated member can constitute a guide rod or stick and the flexible elongated member can be a cord or a string. The cord can be connected with the coupling element in such a manner that its end can pivot about an axis which is tangential to the hoop.

The guide rod and the string can be used to turn the coupling element on the hoop while the latter rolls along the ground so as to shift the point of connection between the cord and the coupling element from one side of the hoop to the other side, or vice versa. Thus, a single rod and a single cord suffice to propel the hoop along the ground as well as to change the direction of movement of the hoop.

If the coupling element is a ring, it is preferably recessed into the hoop so as to avoid bumpy runs while the hoop rolls along the ground. To this end, the hoop can be provided with a recess which is machined into or otherwise formed in its peripheral surface to receive a portion of the ring-shaped coupling element. The aforementioned abutment means then constitutes the surfaces which flank the recess and hold the coupling element against excessive movement in the circumferential direction of the hoop. The hoop may be formed with a second recess which is machined into or otherwise formed in its internal surface opposite the first mentioned recess and also serves to receive a portion of the ring-shaped coupling element. The recesses are large enough to allow for substantially unimpeded turning of the coupling element relative to the hoop whenever the user decides to shift the point of connection between the coupling element and the cord from the one to the other side of the hoop or vice versa.

A bumpy run of the hoop can be avoided completely if the recess in the peripheral surface of the hoop is deep enough to completely accommodate the corresponding portion of a ring-shaped coupling element.

The point of connection between the string and a ring-shaped coupling element should remain fixed. For example, a flexible eyelet can be inserted into an axially parallel hole of the ring-shaped coupling element and the end of the cord can extend through the eyelet.

The novel features which are considered as characteristic of the invention are set forth in particular in the appended claims. The improved toy device itself, however, both as to its construction and its mode of operation together with additional features and advantages thereof, will be best understood upon perusal of the following detailed description of certain specific embodiments with reference to the accompanying drawing.

BRIEF DESCRIPTION OF THE DRAWING

FIG. 1 is an enlarged view of the encircled part A of the toy device shown in FIG. 6;

FIG. 2 is a sectional view as seen in the direction of arrows from the line 2—2 of FIG. 1 and illustrates the position of a ring-shaped coupling element as shown in the encircled part B of FIG. 7;

FIG. 3 is a similar sectional view but showing the position of the ring-shaped coupling element as illustrated in the encircled part C of FIG. 8;

FIG. 4 is an enlarged view of the encircled part D of the toy device shown in FIG. 9;

FIG. 5 illustrates the structure of FIG. 1 and further shows a modified connection between the coupling element and the cord;

FIG. 6 is a perspective view of the toy device in actual use, showing a first stage when the user is about to accelerate the hoop;

FIG. 7 is a similar perspective view but showing a second stage when the user is in a position to change the direction of travel of the hoop;

FIG. 8 is a similar perspective view of the toy device, showing the connection between the cord and the coupling element at one side of the hoop; and

FIG. 9 is a similar perspective view but showing the hoop in a different angular position.

DESCRIPTION OF THE PREFERRED EMBODIMENTS

Referring first to FIGS. 6 to 9 which illustrate different phases or stages of manipulation of the toy device, it will be seen that one end portion of a guide rod or stick 11 is connected with a hoop 12 by means of a string or cord 13 and a ring-shaped coupling element 14 (hereinafter called ring). The ring 14 is mounted for turning movement about the adjacent portion of the hoop 12 which is provided with abutment means to restrict the movement or gliding of the ring 14 in the circumferential direction of the hoop. The parts 11 and 13 respectively constitute a rigid or substantially rigid and a flexible member of a composite steering and driving device for the hoop 12.

Referring now to FIGS. 1 to 4, the peripheral surface of the hoop 12 is formed with a transversely extending recess or groove 15 which can receive the adjacent portion of the ring 14. A similar transversely extending recess or groove 16 is provided in the internal surface of the hoop 12 opposite the recess 15 to receive the adjacent portion of the ring 14, at least in certain angular positions of the hoop 12. The aforementioned abutment means for the ring 14 includes the radially extending surfaces which flank the recesses 15 and 16. The cross-sectional area of the hoop portion between the recesses 15, 16 is selected in such a way that the ring 14 is free to turn on the hoop 12 and that it has a certain freedom of movement in many other directions without being permitted to move entirely beyond the recess 15 and/or 16, as considered in the circumferential direction of the hoop. In other words, a portion of the ring 14 invariably extends into at least one of the recesses 15, 16 even though it is possible (see FIGS. 2 or 3) to select the internal diameter of the ring 14 in such a way that the latter can leave the recess 15 while extending into the recess 16 or vice versa. The depth of the recess 15 preferably exceeds somewhat the width of the ring 14 (as considered in the radial direction thereof) to insure that the ring 14 need not extend beyond the peripheral surface of the hoop when the recess 15 is adjacent to the ground. This reduces the likelihood of hobbling of the hoop.

The cord 13 is tied to the ring 14 by means of the knot. As shown in FIGS. 2 and 3, the ring 14 is formed with an axially parallel hole 17 through which the cord 13 extends. This hole enables the cord to pivot relative to the ring 14 about an axis which is substantially tangential to the hoop 12. If desired, one can employ an eyelet 18 (shown in FIG. 5) which is inserted into the hole 17 of the ring 14 and is tied to the adjacent end of the cord 13 by means of a knot similar to the knot shown in FIGS. 1-4. The eyelet 18 preferably consists of flexible or elastic material and is preferably pivotable in the hole 17 of the ring 14. It will be noted that

the point of connection between the ring 14 and the cord 13 cannot travel in the circumferential direction of the ring, irrespective of whether the cord is tied directly to the ring 14 or is connected to the ring by the eyelet 18.

FIGS. 6-9 illustrate various phases in manipulation of the hoop 12. The arrow P indicates the direction of rotation of the hoop while the latter rolls along the ground.

When the hoop 12 assumes the angular position shown in FIG. 6, the angular position of the ring 14 corresponds to that shown in FIG. 1. The hole 17 of the ring 14 is located at the right-hand side of the hoop 12. By exerting upon the string 13 a pull in the direction indicated by arrow Q, i.e., by quickly lifting the guide rod 11, the operator imparts to the hoop 12 a driving momentum in the direction indicated by the arrow P. The pull simultaneously influences the direction of movement of the hoop 12; the hoop 12 is given a momentum

in a direction to the left, and this momentum increases with the pull upon the string 13. If the string 13 is kept taut, the ring 14 rotates about the hoop 12, so that its knot will be located substantially in the central plane of the hoop 12 (FIG. 2). The portion of the ring 14 opposite the knob is now fully received in the recess 16.

When the hoop 12 and the ring 14 assume the positions illustrated in FIGS. 2 and 7, the user can move the combined steering and driving device 11, 13 back to the right-hand side of the hoop 12 with a short swing of the cord 13 in a direction to the right or to the left-hand side of the hoop 12 with a short swing of the cord 13 in a direction to the left. The two lateral positions of the knot are indicated in FIG. 2 by phantom lines. The two possible lateral movements of the cord 13 are indicated by a double-headed arrow R.

If the user of the hoop 12 selects to move the steering and driving device 11, 13 (and hence the knot) to the left-hand side of the hoop, the knot will remain in the left-hand side of the hoop as long as the user relaxes the tension of the cord 13 (see FIGS. 3 and 8). When the ring 14 reaches the ground (while the pull upon the string 13 is relaxed), the ring is automatically caused to enter the recess 15 so as to insure smooth rolling of the hoop.

When the knot ascends after having reached its lowest position in relation to the ground (see FIG. 9), a pull can be exerted in the direction indicated by arrow S while the device 11, 13 remains at the left-hand side of the rolling hoop 12. This imparts to the hoop a fresh driving momentum and simultaneously tends to steer the hoop in a direction to the right with a force which is proportional to the magnitude of pull. Thus, and in order to insure that the hoop 12 will roll along a substantially straight path, the user must change the position of the knot from the one to the other side of the hoop whenever the knot reaches the uppermost position shown in FIGS. 2 and 7. If the hoop 12 is to roll along a left-hand curve, the knot must be swung in a direction to the right whenever the ring 14 reaches the position shown in FIG. 7 and, if the hoop 12 is to make a sharp curve, the user should also exert a relatively strong pull (arrow Q in FIG. 6) while the hole 17 travels upwardly. The manipulation of the hoop 12 by way of the device 11, 13 is analogous if the hoop 12 is to make a right-hand curve.

It will be seen that, with relatively little skill which can be acquired after a short period of training, a male

or female child can steer the hoop 12 along a straight path or can cause the hoop to travel along a more complex path by the simple expedient of shifting the hole 17 from the one to the other side of the hoop and by exerting on the cord 13 a pull of variable magnitude while the knot travels upwardly. The hoop 12 can be driven at any desired speed, i.e., while the operator walks, jogs or runs.

The improved toy device is susceptible of many further modifications without departing from the spirit of the invention. For example, the illustrated hoop 12 of polygonal cross-sectional outline can be replaced with a hoop having an oval or circular outline. If the cross section of the hoop is circular or oval, the recesses 15, 16 can be replaced with a circumferentially complete groove which receives the ring-shaped coupling element 14 or an analogous coupling element. Also, and especially if the coupling element is relatively thin, the just mentioned groove or the recesses 15, 16 can be omitted and the hoop can be provided with outwardly extending abutment means (for example, on one or both side faces thereof) to enable the coupling element to turn about the hoop while simultaneously holding the coupling element against movement in and counter to the direction indicated by the arrow P. The material of the hoop 12, coupling element 14 and/or rod 11 can be metal, plastic, wood or a combination of such materials. Furthermore, the parts 11, 13 can be replaced with a one-piece driving and steering device which may include a relatively rigid and a flexible or deformable portion. If desired, the hoop can be manipulated only by means of the cord 13. The coupling element 14 may be a split ring so as to be readily connectable to and separable from the hoop. The same applies for the eyelet 18 of FIG. 5.

Without further analysis, the foregoing will so fully reveal the gist of the present invention that others can, by applying current knowledge, readily adapt it for various applications without omitting features which, from the standpoint of prior art, fairly constitute essential characteristics of the generic or specific aspects of my contribution to the art and, therefore, such adaptations should and are intended to be comprehended within the meaning and range of equivalence of the claims.

What is claimed as new and desired to be protected by letters Patent is set forth in the appended claims:

1. A toy device comprising a hoop arranged to roll along the ground; a coupling element mounted for turning movement about said hoop, said hoop having abutment means for restricting the movement of said coupling element in the circumferential direction of said hoop; and a combined steering and driving device including a manually operable elongated flexible member having an end portion connected with said coupling element for pivotal movement relative to said coupling element about an axis which is substantially tangential to said hoop.

2. A toy device as defined in claim 1, wherein said coupling element is a ring.

3. A toy device comprising a hoop arranged to roll along the ground and having an internal surface and a peripheral surface; a first transversely extending recess provided in said internal surface and a second trans-

versely extending recess provided in said peripheral surface opposite said first recess, said recesses bounded by additional surfaces flanking said recesses and constituting abutment means; a coupling element mounted for turning movement about said hoop and engaging at least one of said recesses so that movement of said coupling element is restricted in circumferential direction of said hoop; and a combined steering and driving device including a manually operable elongated member connected with said coupling element.

4. A toy device as defined in claim 1, wherein said elongated flexible member has a second end portion and said combined steering and driving device further includes an elongated rigid member arranged to be held by hand and connected with said second end portion of said elongated flexible member.

5. A toy device as defined in claim 4, wherein said elongated flexible member is a string or cord and said elongated rigid member is a rod or stick.

6. A toy device as defined in claim 1, wherein said hoop has at least one transversely extending recess and surfaces flanking said recess, said coupling element having a portion extending into said recess and said surfaces constituting said abutment means for said coupling element.

7. A toy device as defined in claim 6, wherein said hoop has a peripheral surface and said recess is provided in said peripheral surface thereof, the depth of said recess being sufficient to fully accommodate the adjacent portion of said coupling element so that said coupling element need not contact the ground during rolling of said hoop.

8. A toy device as defined in claim 1, wherein said hoop has a polygonal cross-sectional outline.

9. A toy device comprising a hoop arranged to roll along the ground; a coupling element mounted for turning movement about said hoop, said hoop having abutment means for restricting the movement of said coupling element in the circumferential direction of said hoop; and a combined steering and driving device including a manually operable elongated member having an end portion; an eyelet articulately connected with said coupling element and with said end portion of said elongated member of said driving and steering device for connecting said end portion of said manually operable elongated member to said coupling member pivotably about an axis which is substantially tangential to said hoop.

10. A toy device as defined in claim 9, wherein said eyelet is deformable.

11. A toy device comprising a hoop arranged to roll along the ground; a ring-shaped coupling element having a hole, and mounted for turning movement about said hoop, said hoop having abutment means for restricting the movement of said coupling element in the circumferential direction of said hoop; and a combined steering and driving device including a manually operable elongated flexible member having an end portion extending through said hole of said ring-shaped coupling element and forming a knot which connects said elongated member to said ring-shaped coupling element.
